Attorneys.

UNITED STATES PATENT OFFICE.

JAMES H. RAND, OF NEWTON, MASSACHUSETTS.

INDEX MEMBER.

1,255,226.

Specification of Letters Patent.

Patented Feb. 5, 1918.

Application filed December 30, 1916. Serial No. 139,795.

To all whom it may concern:

Be it known that I, JAMES H. RAND, a citizen of the United States, and resident of Newton, in the county of Middlesex and

5 State of Massachusetts, have invented new and useful Improvements in Index Members, of which the following is a specification.

This invention relates to index members for so-called visible indexes of the type in 10 which a series of overlapping cards or sheets are supported in a frame by means of supporting bars or carriers the ends of which are inserted in opposed guide channels of the frame. The cards are attached at one 15 edge to the bars or carriers while the opposite edges are free, so that the cards may be swung on their bars or carriers to permit the inspection or making of entries on underlying cards, while in normal position the 20 cards overlap one another with their free margins exposed to display indexing matter.

In the accompanying drawings which illustrate one embodiment of the invention,

25 Figure 1 is a front face view of an index member containing the invention;

Fig. 2 is an enlarged section on line 2—2 of Fig. 1; and

30 Fig. 3 is a rear face view of the index member.

A represents a card sheet constituting the body of the index member, to the upper edge of which is secured a strip B of textile fabric or other suitable material. The strip B, if 35 of fabric, is suitably stiffened to support the weight of the card, and may be provided with tabs b, coated with an adhesive gum for attachment to the edge of the card A. C is the supporting bar or carrier, in the 40 form of a sheath of sheet celluloid or other suitable resilient material, having a flat front face c, a flat rear face c' and an in-turned lip c² bent up from the edge of the face c' opposite the fold between the faces c and c'. Thus the sheath C constitutes a sub- 45 stantially closed tube into which the folded margin b' of the supporting strip B may be inserted by sliding the same lengthwise in the tubular sheath C. The card A swings on

50 the fabric supporting strip as a hinge. The ends of the sheath C project beyond the side edges of the card A to engage the usual guide channels of the frame (not shown) for supporting and spacing the cards. It 55 will be understood that other forms of supporting bars and other modes of attachment

of the card thereto may be employed. The particular forms described constitute no part of the present invention but are reserved for separate application.

60

The opposite margin of the card or sheet A is provided with an offset margin a, which is preferably integral with the body of the card, and may be formed by bending or pressing the margin of the card, with 65 suitable dies or otherwise, folding the same on three parallel lines to form a trough-like structure with three closed walls, namely, a connecting wall or shoulder a', a wall a, and a terminal wall or flange a², the fourth side 70 of the box-like structure thus formed being open.

The offset margin a is covered by a sheath D of transparent, sheet material, such as sheet celluloid, bent or folded to 75 form a flat front face d, overlying the open, hollow or recessed side of the offset structure, a flat rear face d' covering the rear side of the offset margin, and an inturned retaining lip d² on the extremity of the 80 rear side d', to engage the shoulder a' of the offset margin. The sheath D is removable from the offset margin by sliding the sheath endwise on the margin. The face d of the sheath D preferably extends inwardly over 85 the face of the card or sheet A beyond the offset margin so that the next adjacent overlying index card, when a series of similar members are mounted in the frame, will rest at its lower edge on the face d and slip 90 readily thereon without catching, when a number of the cards are swung upwardly on their hinges. The relation of the extension face d to the next overlapping card is shown in dotted lines in Fig. 2.

95

In the recess formed between the offset margin a and the face d of the sheath, is a removable indicator strip E of paper or other suitable sheet material for receiving suitable index data or inscriptions appropriate to the entries on the card or sheet A.

100

This construction with the offset margin and the flat faced sheath which lies substantially flush with the face of the card A, produces an index element for an overlapping 105 card index in which the free or exposed margin of the card may carry a protective transparent sheath and a removable indicator strip at the front side of the card, all presenting a flat, smooth front surface substantially flush with the front surface of the body of the card, and free from any for-

110

wardly projecting tubular sheath and index strip, which would stand in relief from the face of the card but for the offset margin α . The inserted strip E may thus lie substantially in the plane of the body A of the card itself, so that the face of the index member as a whole presents no more salient projections nor structures in relief from the face of the card which might catch on an adjacent card than a plane flat card protected at the margin with a flat sheet of celluloid, but without any indicator strip or other insert.

It will also be understood that this offset margin could be used at the upper edge of the card, or at both the upper and lower edges. In either case the offset structure affords an admirable form of connection between the card and the sheath capable of detachment by sliding the sheath endwise of the card margin.

I claim:

An index member comprising a sheet having an offset margin extending completely across one edge of the sheet, a sheath of 25 transparent material embracing said offset margin, having a flat front face extending across the recess formed by the offset margin and an inturned lip on its rear side engaging the shoulder of the offset margin, 30 said sheath being open and unobstructed at both ends whereby said sheath is removable from the sheet by sliding the same lengthwise of the offset margin, and forms with the offset margin a hollow strip holder open 35 at both ends, and a removable indicator strip adapted to slide endwise into and out of said open ended strip holder.

Signed by me at Boston, Massachusetts, this 28th day of December, 1916.

JAMES H. RAND
